UNITED STATES PATENT OFFICE.

MARTIN MARTINSON, OF PRINCETON, ILLINOIS.

SHIELD.

Application filed March 23, 1923. Serial No. 627,066.

To all whom it may concern:

Be it known that I, MARTIN MARTINSON, a citizen of the United States, residing at Princeton, in the county of Bureau and 5 State of Illinois, have invented a certain new and useful Improvement in Shields, of which the following is a specification.

This invention relates to a portable shield which is designed to be carried so as to protect the user from bullets. It has for one 10 object to provide a light, portable shield which may be used by police and other officers to protect the user from bullet fire, and also to provide means whereby he may 15 direct his own firing against an assailant, while still being protected. Other objects will appear from time to time throughout the specification and claims.

My invention is illustrated more or less 20 diagrammatically in the accompanying drawing, wherein:

Figure 1 is a front elevation of the device of the invention;

Figure 2 is a perspective of the rear;

25 Figure 3 is a vertical cross section taken on line 3—3 of Figure 1.

Like parts are designated by like characters throughout.

A is a shield provided with the reduced 30 upper portion B, which is here shown as rounded. The entire shield is curved as shown particularly in Figure 3 and is provided about its edge with a reversed curve C. The purpose of this curve is to deflect bullets and fragments of bullets which strike 35 near the edge of the shield, or which are deflected from the shield, to prevent their passing to the rear. The reversed curve causes them to pass again to the front, or at least 40 deflects the fragments of the bullet so that they do not splatter in the rear of the shield.

D is an opening in the front of the shield. It may be used for observation or may be used to fire through. It is closed by a piv- 45 oted cover D¹, which as here shown is mounted in the rear of the shield. It may be in the front but it is preferably mounted in the rear.

E, E are hand and arm holding elements 50 mounted in the rear of the shield, through which the arm and hand of the user is placed and by means of which the shield is held.

In use the shield is held preferably on the left arm of the user and will protect the 55 body. In one form the shield is about forty inches in height. The user may carry the shield in front of him as he advances and may use the hole either for observation purposes or to shoot through.

I claim:

1. In a protective shield, a shield body having a convex face, the edges of said body being slightly recurved, arm engaging supporting means secured to the rear of said shield, a peep-hole adjacent the top thereof, and a cover therefor operable from the rear of the shield, the shield being of reduced size adjacent its top.

2. In a protective shield, a shield body having a convex face, the entire edge of said shield being slightly recurved, arm engaging supporting means secured to the rear of said shield, a peep-hole adjacent the top thereof, and a cover therefor operable from the rear, the shield being of reduced size adjacent its top.

Signed at Princeton, county of Bureau and State of Illinois, this 20th day of March, 1923.

MARTIN MARTINSON.
